MACHINE FOR TREATING SHOES

**Adrien L. Jalbert, Haverhill, Mass., assignor to
United Shoe Machinery Corporation, Borough
of Flemington, N. J., a corporation of New
Jersey**

Application June 17, 1939, Serial No. 279,706

22 Claims. (Cl. 12—51)

This invention relates to machines for treating shoe uppers to improve their appearance and particularly to machines for treating parts of the uppers adjacent to the foot openings including, when they are present, the tongues and eyelet flies.

When shoes have been substantially completed, it is often found that the uppers are wrinkled and the top edges of the linings are exposed, and that the eyelet flies are widely separated from each other so that the shoes present an unattractive appearance.

It is an object of this invention to provide a machine for operating upon shoes in this condition to give them a presentable appearance by smoothing and shaping the tongues and parts of the uppers adjacent the foot openings, and by pressing the eyelet flies toward each other into the position they assume when laced. To this end, and in accordance with one feature of the invention, the illustrated machine is provided with tongue shaping means arranged to press the tongue portion of a shoe and give it a transverse curvature that approximates the transverse curvature of the instep portion of the shoe, and an expandible shoe form for pressing the tongue and the tongue shaping means against one another.

In the illustrated embodiment of this invention, the tongue shaping means comprises flexible metal plates arranged to receive the tongue portion of a shoe between them. These plates are disposed between upper ironing members and the expansible shoe form so that upon the expansion of the latter the plates are squeezed between the form and the ironing members; the ironing members acting as abutments in that they support the plates against outward pressure from the form. As disclosed, the plates are provided with heating means for increasing the effectiveness of its ironing and shaping action upon the tongue which is pressed against it.

Viewing this invention from another aspect and having in mind the difficulties encountered when carrying out upper shaping operations upon shoes of various sizes and styles in machines using rigid forms, there is provided, in accordance with another feature of this invention, a machine having ironing means arranged for engagement with the upper portion of a shoe around its foot opening and an inflatable shoe form for pressing the uppers against the ironing means. As illustrated, the ironing means consists of a pair of heated upper ironing members having their work engaging faces shaped for engagement with the eyelet flies and the rearwardly extending portion

of the uppers adjacent the foot receiving openings. The ironing members, when used in combination with the aforementioned tongue engaging plate, overlie the plate and support it against outward pressure from the shoe form.

These and other features of the invention will appear more fully from the following detailed description when read in connection with the accompanying drawings and will be pointed out in the appended claims.

10 the appended claims.

In the drawings, Fig. 1 is a side elevation of a machine embodying the present invention;

Fig. 2 is a front elevation of a portion of the machine shown in Fig. 1;

Fig. 3 is a view taken along line III—III of Fig. 1 looking in the direction of the arrows;

Fig. 4 is a view taken along line IV—IV of Fig. 2 looking in the direction of the arrows and illustrating the construction of the inflatable shoe form and the tongue pressing members; and

Fig. 5 is a view taken along line V—V of Fig. 1 looking in the direction of the arrows.

The illustrated machine comprises a frame 10 (Fig. 1) adapted to be mounted on a base or table 12 and secured thereto by the usual fastening means, such as bolts or the like, the frame consisting of a base portion 14 having a forwardly

extending gooseneck 16 which terminates in a head 18 and a downwardly extending arm 20 upon which is mounted an inflatable shoe form 22 (Fig. 4). The inflatable shoe form 22, which will hereinafter be referred to as the form, is supported by a flat plate 24 (Fig. 4) which underlies the bottom of the form and is connected to the arm 20 by a rectangular stud 26 that extends through a complementarily shaped airtight pas-

through a complementally shaped air-tight passage **28** in the form **22**. The form **22**, which may be made of rubber or like material, is shaped to agree with the front and sides of the top portion of a last and is of approximately half the height of a last (Fig. 3) so that it can fit readily into shoes of different sizes. When the form **22** is inflated, downward expansion is restricted by the underlying plate **24**, and upward expansion of the unconfined portion of the form which lies in the foot receiving opening of a shoe is restricted by a horizontally extending arm **36** (Figs. 1 and 4).

50 of a bracket 32 which is connected to the arm 20 by a screw 34. The horizontally extending bracket arm 36 projects beyond the rear end of the form 22 (Fig. 1) so that it will overlie the heel portion of a shoe when it is placed upon the 55 form and thus will also act as a gage and assist

the operator in correctly positioning the heel portion of a shoe as he places it on the form.

Overlying the form 22 (Fig. 4) are a pair of thin metallic tongue engaging plates 38 and 40 which are loosely connected to the arm 20 by a stud 42. These plates are angularly constructed so that their upper portions will be substantially vertical and lie along the side of the arm 20 while their lower portions are inclined downwardly and forwardly toward the operator. The lower tongue receiving portions of the plates 38 and 40 are urged apart by a spring 44 sleeved on a stud 46 which passes loosely through the upper ends of the plates into engagement with the arm 20, the spring 44 normally holding the lower portions of the plates 38 and 40 apart so that the tongue portion of a shoe may readily be inserted between them as the shoe is being placed on the form 22.

While the tongue engaging plates 38 and 40 will give a transverse curvature which approximates the shape of the instep portion of a shoe, they are flexible enough so that they may be bent as they are squeezed together to iron the tongue. This enables the application of uniform pressure throughout the whole of the tongue regardless of the relative thicknesses of various portions thereof. The ability of the tongue plates 38 and 40 to conform to work of varying thicknesses is important because the leather used for shoe tongues is of very poor quality and is not at all uniform in thickness.

Located on either side of the form 22 are upper shaping or ironing members 50, 52 (Fig. 2) which have their work contacting surfaces shaped for engagement with the eyelet flies and the upper of a shoe on the shoe form 22. In the illustrated embodiment of this invention the ironing members 50, 52 extend rearwardly from the eyelet flies along the shoe upper to a point about opposite to the forward edge of the counter (Fig. 1); however, they may be extended to the back seam if desired. It is to be noted that when the ironing members 50, 52 are in engagement with the upper of a shoe S on the form 22 (Fig. 3) they overlie the somewhat flexible thin tongue engaging plates 38 and 40 and support them against outward pressure exerted by the form 22.

The ironing members 50, 52 are moved into and out of engagement with the upper of a shoe on the form 22 by crossed levers 54, 56 which are pivoted on the head 18 directly above the form. As the connections between the levers 54, 56 and the upper ironing members 50, 52 are similar, only one of these connections will be described and like numerals will be given to corresponding connecting parts between both of the levers and the ironing members carried by them. The upper ironing member 50 is connected to the lever 54 by a heavy spring 60 and a rod 58 which is slidably mounted in the end of the lever 54. The rod 58 is mounted in alined openings in spaced bosses 62, 64 formed on the end of the lever 54 and is urged in a downward direction by a light spring 66 which is sleeved on the rod 58 between the boss 64 and a shoulder 68 on the rod 58. The heavy spring 60, fastened at its ends to the rod 58 and the ironing member 50, forms a universal connection between them which permits the ironing member to tilt, thereby to adjust itself to the shoe on the form 22 as the form is being inflated, while the light spring 66 permits a limited upward movement of the ironing member 50 and the rod 58 in response to the expansion of the form 22. Upward movement of the ironing member 50 and rod 58 is limited by the engagement

of a shoulder 70 on the lower end of the rod 58 with the boss 62. When the ironing member 50 is seated against a shoe on the form 22, twisting strains are set up through the spring 60 which tend to rotate the rod 58, and, if the rod were permitted to rotate under these strains, the position of the ironing member would be changed when the ironing member was moved away from the shoe at the completion of a shaping operation. This undesired rotation of the rod 58 in the bosses 62, 64 is prevented by a forked plate 72 which is clamped to the upper end of the rod 58 between nuts 74, 76, and has its forked end seated over the upper end of the lever 54 (Fig. 2).

The upper ends of the levers 54, 56 are connected to a lug 88 on a vertical slide 82 by short links 84, 86 which, when the slide is in its lower position (Fig. 2), form an expanded toggle joint that holds the levers 54, 56 and the ironing members 50, 52 mounted on those levers away from the form 22. The slide 82 is mounted in ways formed in the head 18 and is moved upwardly to collapse the toggle joint and move the ironing members 50, 52 against a shoe on the form 22 by a rearwardly extending lever 78 (Fig. 1) which in turn is operated by a treadle 90 through a treadle rod 92. The lever 78 is pivoted on the goose-neck 16 by an interconnecting link 80 and is connected at its forward end (Fig. 1) to the slide 82 by a link 81. At its rearward end the lever 78 is connected to the treadle rod 92 by a pivotally attached sleeve 96, (Figs. 1 and 5) which is slidably mounted on the rod 92 between a collar 98 fast to the rod and a spring 100 sleeved on the rod and confined by nuts 102 threaded on the end of the rod. As a result of the construction just described, when the treadle 90 is moved downwardly, force will be transmitted to the lever 78 through the spring 100 causing the lever 78 to raise the slide 82 and move the ironing members into engagement with the upper of a shoe on the form 22. The spring 100 is adjusted so that it will yield after the ironing members 50, 52 are pressed lightly against the shoe on the form 22.

Inflation of the form 22 is accomplished through a pump 106 which is mounted on the floor and is connected to a nipple 107 on the inflatable form 22 by a flexible hose 108 through a coupling containing a suitable relief valve 110. The relief valve 110 is controlled by an arm 116 which, when in its upper position (Fig. 1), holds the valve open and permits air to escape from the form 22 and in its lower position closes the valve. Underlying the valve arm 116 is a finger 118 on a block 120 fast to the treadle rod 92, the arrangement being such that the valve arm 116 is held in its upper position by the finger 118 when the treadle is raised (Fig. 1) and upon depression of the treadle the valve arm 116 follows the finger 118 downwardly under the urging of a spring 122 closing the valve 110. The pump 106 is operated by the treadle 90 through a link 112 which is connected at one end to the treadle 90 and at the other end to the stem 113 of the pump piston 114. Thus, upon depression of the treadle 90 the ironing members 50, 52 are moved inwardly into engagement with the upper of a shoe on the form 22 and the piston 114 is moved downwardly in the pump cylinder inflating the form 22. It is desired to have the ironing members 50, 52 engage the shoe upper before the form 22 is inflated and this is effected by adjusting the finger 118 on the treadle rod 92 so that the

relief valve 110 closes at about the time the ironing members contact the shoe on the form.

The treadle 90 moves through a slot in a guide 128 and is normally held against the upper end 130 of the slot by a heavy spring 94 which is connected at one end to the table 12 and at its other end to the treadle 90. After the treadle 90 has been moved downward sufficiently to operate the machine in a desired manner it is moved laterally so as to bring a treadle tooth 124 thereon into engagement with one of the teeth 126 formed in the side of the slot in the guide 128 and is thus held depressed for such time as the operator wishes to subject the shoe to the action of the machine.

The ironing members 50, 52 and the upper tongue engaging plate 38 are heated by resistance units 132, 134 and 136 (Fig. 3), respectively, to increase the effectiveness of their smoothing and shaping action. The resistance units 132, 134, 136 are connected to a source of power by leads (Fig. 1) which extend through a conduit 138 to a junction box 140 mounted on the table 12.

The operation of the machine is as follows: After a shoe S has been placed on the form 22 with its tongue portion T between the plates 38, 40 and its heel portion against the rear of the form 22 and the projecting portion of the horizontal bracket arm 36, the treadle 90 is depressed to move the heated ironing members 50, 52 lightly into engagement with the upper of the shoe S and to inflate the form 22 so that the latter will press the tongue and upper against the heated plate 38 and the ironing members 50, 52. Due to the arrangement of the finger 118, the relief valve 110 is held open during the first portion of the downward movement of the treadle 90 and, as the ironing members are brought into engagement with the shoe S, the valve is closed and further downward movement of the treadle 40 causes the inflation of the form 22. If the treadle 90 should be depressed too far so as to cause the over inflation of the form 22 the light springs 66 would yield until the shoulders 70 on the spindles 58 engaged the bosses 62 thereby permitting the ironing members to move backwardly that amount. If the form 22 should be further inflated by a repeated pumping action of the treadle 90 in the lower portion of its downward path of movement, the spring 100 would then yield permitting the ironing members 50, 52 to move back further under the additional pressure exerted by the form 22. It will be understood from the above explanation that the principal function of the form 22 is to press the plates 38, 40 against the tongue and to press the uppers lightly but firmly against the ironing members 50, 52 and that the smoothing and shaping function is due primarily to the action of the heated ironing surfaces on the plate 38 and the ironing members 50, 52 upon the work surfaces pressed against them by the form 22. When the form has been inflated to a desired extent the treadle 90 is moved laterally into holding engagement with one of the teeth 126 on the guide 128 where it is held for such time as is necessary to carry out the ironing and shaping operation upon the shoe S. At the completion of this operation, the treadle is released and is moved upwardly by the spring 94, this movement of the treadle opening the valve 110 and moving the ironing members 50, 52 back away from the form 22 so that the shoe may be removed from the machine.

Having thus described my invention, what I

claim as new and desire to secure by Letters Patent of the United States is:

1. In a machine for treating shoe parts, a shaping member arranged for engagement with a surface of the tongue portion of a shoe, and an expandible form for pressing the tongue portion against the shaping member.

2. In a machine for treating shoe parts, a heated metal plate arranged for engagement with the tongue portion of a shoe, and an expandible shoe form for pressing the tongue portion against the heated metal plate.

3. In a machine for treating shoe parts, a heated metal plate arranged for engagement with the tongue portion of a shoe, an expandible shoe form for pressing the tongue against the heated metal plate, and means for supporting the plate against the pressure from the expandible shoe form.

4. In a machine for treating shoes, a plate arranged for insertion between the tongue portion of a shoe and the eyelet flies, an expandible shoe form for pressing the tongue against the plate, and means for engaging the eyelet flies and supporting them and the underlying plate against outward pressure from the expandible shoe form.

5. In a machine for treating shoes, an expandible shoe form, a metal plate arranged for insertion between the tongue portion of a shoe on the form and the eyelet flies of that shoe, upper engaging members constructed and arranged for engagement with the upper from the eyelet flies to the counter, said members supporting the upper and plate against the outward pressure of the expandible shoe form, and means for heating the upper engaging members.

6. In a machine for shaping shoe parts, coacting transversely curved thin flexible metal plates between which the tongue of a shoe may be positioned, adjacent ends of said plates being secured to said machine, means for separating the other ends of said plates to facilitate the insertion of the work, and means for squeezing said plates together to smooth the tongue, said means comprising an abutment coacting with one of said plates and having approximately the curvature of the related plate.

7. In a machine for pressing shoe tongues, coacting flexible metal plates having approximately the transverse curvature of the instep portion of a shoe, means for heating one of said plates, means for separating said plates to permit the interpositioning of a shoe tongue, means for pressing said plates against the tongue comprising an abutment associated with one of the plates and a yielding presser member associated with the other plate, and means for causing relative movement between the presser member and the abutment to iron the tongue.

8. In a machine for treating shoes, an expandible shoe form, a heated metal plate arranged for insertion between the tongue portion of a shoe on the shoe form and eyelet flies of that shoe, heated upper engaging members mounted for tilting movement, and means for yieldingly holding said heated upper engaging members against the outer surface of the instep portion of a shoe on the shoe form to support the heated metal plate against outward pressure from the expandible shoe form and to remove the wrinkles from that portion of the shoe.

9. A machine for treating shoe parts comprising an expandible shoe form, means for expanding said shoe form, heated ironing members

adapted for engagement with the upper of a shoe on the expandible shoe form, and yieldable supporting means for the heated ironing members arranged to hold said members against the upper of a shoe on the shoe form and to regulate the pressure exerted on the uppers by the ironing members and the expandible shoe form.

10. A machine for treating shoe parts comprising an inflatable shoe form, a metal plate arranged for insertion between the tongue portion of a shoe on the inflatable shoe form and the eyelet flies of that shoe, and heated ironing members arranged for engagement with the eyelet flies overlying the metal plate to support the instep portion of the shoe against outward pressure from the inflatable shoe form.

11. A machine for treating shoe parts comprising an inflatable shoe form, a heated metal plate arranged for insertion between the tongue portion of a shoe on the shoe form and the eyelet flies of that shoe, ironing members constructed and arranged for engagement with the eyelet flies overlying the metal plate, and means for moving the ironing members into engagement with the eyelet flies, said means comprising carriers for the ironing members arranged for movement toward and away from the inflatable form and spring means for connecting the ironing members to the carriers.

12. In a machine for treating shoe parts, an inflatable shoe form, ironing members arranged for engagement with the upper of a shoe on the inflatable form, and means for moving said ironing members into engagement with a shoe upper on the form and for inflating the form to press the upper against the ironing members.

13. A machine as defined in claim 12 having a metal plate arranged for insertion between the tongue portion of a shoe on the form and eyelet flies of that shoe, and means for heating the metal plate and the ironing members.

14. A machine for treating shoe parts comprising a support, an inflatable shoe form mounted on the support, metal plates arranged for engagement with the opposite surfaces of the tongue portion of a shoe on the shoe form, upper ironing members shaped for engagement with the eyelet flies of the shoe on a shoe form, resilient means for supporting the upper ironing members, and means for first moving the upper ironing members into engagement with the uppers and then inflating the form to force the uppers outwardly against the upper ironing members.

15. In a machine for treating shoe parts, an inflatable shoe form, means for inflating the shoe form comprising a pump and a valve, ironing members arranged for engagement with the upper of a shoe on the shoe form, and operating mechanism arranged to move the ironing members into engagement with the upper of a shoe on the shoe form and to actuate the valve to cause the inflation of the shoe form after the ironing members have been moved into engagement with the shoe upper.

16. In a machine for shaping shoe uppers, a support, an inflatable shoe form mounted on said support, shoe upper smoothing and shaping means arranged to engage the upper of a shoe on the support about part of the foot opening, and means arranged to prevent the displacement of the unconfined portion of the shoe form in the foot opening when the form is inflated while inserted in a shoe.

17. In a machine for shaping shoes, an inflatable shoe form, a support for said inflatable shoe form, a plate mounted on said support and arranged to prevent the displacement of the bottom portion of the shoe form, and a member on said support arranged to overlie and prevent the displacement of the unconfined portion of the shoe form lying within the foot opening of a shoe on the shoe form, said member being arranged for engagement with the rear portion of a shoe on the shoe form to assist in locating it on the shoe form.

18. A machine for smoothing and shaping shoe uppers comprising a plurality of shaping members arranged for engagement with shoe uppers, means for moving the shaping members into and out of engagement with the upper of a shoe in the machine, and an inflatable inner form for pressing the uppers outwardly against the shaping members.

19. A machine as defined in claim 18 in which means are provided for heating the shaping members.

20. A machine for smoothing and shaping shoe uppers comprising an inflatable shoe form, a pair of metal shaping plates arranged for engagement with the quarter of the upper of a shoe on the shoe form, means for heating the shaping plates, and means for moving the shaping plates into and out of engagement with the upper of a shoe on the inflatable shoe form.

21. A machine for smoothing and shaping shoe uppers comprising an inflatable shoe form, a pair of metal plates having their work-engaging surfaces shaped for engagement with the quarter of a shoe on said shoe form, displaceable members for moving the metal plates into and out of engagement with a shoe upper, and universally movable means for connecting the displaceable members with the metal plates.

22. A machine for smoothing and shaping shoe uppers comprising an inflatable shoe form, a pair of metal plates having their work-engaging surfaces shaped for engagement with the quarter of a shoe on said shoe form, means for heating the metal plates, displaceable members for moving the metal plates into and out of engagement with a shoe upper, spring connections between the displaceable members and the metal plates, and means for inflating said shoe form to press an upper against the metal plates.

ADRIEN L. JALBERT.
